CLAIM

The ornamental design for a toothpaste-dispensing toothbrush, as shown and described.

DESCRIPTION

FIG. 1 is an exploded front elevational view of a toothpaste-dispensing toothbrush showing my new design, the rear elevational view being a mirror image thereof;

FIG. 2 is a side view, taken from the left side of FIG. 1; FIG. 3 is a side view, taken from the right side of FIG. 1;

FIG. 4 is a top plan view thereof;

FIG. 5 is a bottom plan view thereof; and,

FIG. 6 is a rear elevational view of my toothpaste-dispensing toothbrush with its cap in place.
